(57) **CLAIM**

I claim the ornamental design for an engine-turning tool, as shown and described.

DESCRIPTION

FIG. 1 is a front view of the engine-turning tool.

FIG. 2 is a back view of the claimed design.

FIG. 3 is a side view of the claimed design.

FIG. 4 is a top view of the claimed design; and,

FIG. 5 is a bottom view of the claimed design.

On FIGS. 1-5, the handle is depicted in broken line form because it forms no part of the claimed design.
